UNITED STATES PATENT OFFICE.

FELIX E. VOORHIES AND OSCAR V. JONES, OF DALLAS, TEXAS.

PIPE WRENCH.

Application filed March 25, 1922. Serial No. 546,564.

To all whom it may concern:

Be it known that we, FELIX E. VOORHIES and OSCAR V. JONES, citizens of the United States, residing at Dallas, in the county of Dallas and State of Texas, have invented certain new and useful Improvements in Pipe Wrenches, of which the following is a specification.

This invention relates to new and useful improvements in pipe wrenches.

The object of the invention is to provide a pipe wrench that will be highly effective in gripping a pipe either for the purpose of rotating the same, or holding the same against rotation. A particular object is to provide a flexible jaw including gripping elements which may be removed and replaced, and which will readily conform to the contour of the object to be gripped.

Another object of the invention is to provide a releasing device whereby the wrench may be readily disengaged from the object; together with a novel form of carriage for supporting the wrench.

A construction designed to carry out the invention will be hereinafter described together with other features of the invention.

The invention will be more readily understood from a reading of the following specification and by reference to the accompanying drawings, in which an example of the invention is shown and wherein:

Fig. 1 is a plan view of a wrench constructed in accordance with our invention, a portion of the jaw being shown in section,

Fig. 2 is a cross sectional view on the line 2—2 of Fig. 1,

Fig. 3 is a cross sectional view on the line 3—3 of Fig. 1,

Fig. 4 is a sectional view of the bail,

Fig. 5 is a side elevation of the wrench in carriage as shown in Fig. 1, and

Fig. 6 is a cross sectional view on the line 6—6 of Fig. 5.

In the drawings the numeral 10 designates a head in which a handle 11 is inserted and fastened by a bolt 11'. At each side of the block is formed an annular boss 12, having a concaved annular recess therearound, which forms a guide for a cable or other flexible connection 13. The cable 13, is formed into a loop having its ends passed around the bosses. An arm 14 having a disk at its lower end is disposed against each boss. Latches 15 are pivoted in the head and have hooks 15' at their upper ends.

Plungers 16 fastened to the latches pass thru slots in the arms. Coiled springs 16' are confined on the plungers for pressing the latches inwardly. An eye bolt 17 is passed centrally thru the disks of the arms, the bosses, and the head, and receives a nut 18 which is likewise provided with an eye. This provides an eye on the upper side as well as on the lower side of the head, either of which eyes may be engaged with the rigging of the derrick to hold the wrench in a suspended position as is common in this art.

The outer end of the head 10 is bifurcated and provided with a pivot pin 19 so that the hook 20 of a hook lever 21 may be pivoted in the bifurcated head. The lever 21 is arranged to swing down between the latches 15 and engage under the hooks 15' thereof, whereby said lever is held in position. A looped portion of the cable 13 is fastened to a U-shaped bail 22 which is provided with a handle 23. The workman may grasp the handle 23 and engage the bail in the hook 20. On the cable between the bosses and the bail we provide a flexible jaw composed of face blocks 24 and tooth blocks 25. These blocks have their sides cut radially so as to assemble in a segment, the two strands of the cable passing through the upper and lower portions of said blocks as is clearly shown in the drawings. The blocks are spaced from the bail by a sleeve 26 and the jaw is of such length as to surround a sufficient portion of the circumference of the tubular article, to properly grip the same.

The jaw is provided with a tooth member 27, inserted in one side thereof in a suitable manner so as to engage the article gripped by the jaw. The tooth member is preferably of different material than the head and may be removed to sharpen the teeth or replaced when necessary. The space blocks are not as long radially as the tooth blocks so as to permit the tooth spaces of the latter to project inwardly and engage the article A, which may be a pipe or other tubular member. It is obvious that the blocks 24 and 25 may be slipped off the cable and replaced with others, whereby various adjustments and changes may be made in the jaw.

The ends of the cable are carried above and under the handle 11 and passed thru ears 28 in a cross head 29. The cross head is mounted to slide vertically on upright

2
posts 31 passing thru each end thereof, and is fastened on said posts by set screws 32, when desired. Usually the set screws 32 are not fastened so that the cross head is free to slide on the posts. The cross head is sustained by coil springs 33 surrounding the posts thereunder and supported by collars 34 fastened by set screws 35. Anything falling upon the cross head would depress the same and likewise if the wrench was struck the head would also be depressed, whereby the parts would be saved from injury.

A take-up plate 36 is mounted to slide on the handle 11, in rear of the cross head 29, and is provided at each end with adjusting screws 38 bearing against the rear side of said cross head, whereby the plate may be adjusted toward and from the same. The plate is provided with apertures receiving the ends of the cable 13, and has set screws 37 entering said apertures for fastening the ends of the cable therein. This device is arranged for taking up the slack in the cable 13 when the lever 21 is fastened so as to cause the jaw to properly grip the pipe. As an additional support a resilient standard 39 has its upper end bent outwardly and engaging under the head 10. The rear end of the standard is seated in the base 40 of the carriage and is held by a bolt 41. A stud 42 projects from the lower end of the standard so as to engage in a socket 43 in a rotary table. The standard 39 may have a plurality of openings for the pin 41 if necessary. The handle 11 has a plurality of spaced holes 44 adapted to receive a pin 45 carried by the cross head whereby said handle may be adjusted longitudinally and held in position.

40 When the lever 21 is swung outward, the hook 20 is moved toward the article A, so that the bail 22 may be engaged on the same. Then by swinging the lever 21 in between the latches 15, the jaw is drawn around the article whereby the teeth of the blocks 25 engage the same and the member 27 is also drawn into engagement with the opposite side of said article. The wrench and carriage being mounted on a rotary table, it will be seen that when said table is rotated in a clockwise direction, the various teeth will bite into the article A and cause the same to rotate. When it is desired to release the wrench, it is merely necessary to spring the latches 15 apart. This is accomplished by a release lever 46 which is pivoted on the upper end of a bolt 47 passing thru the lever 21. The lever 46 carries a spreader 48, which engages between the hooks 15'. A keeper 49 is provided for guiding the lever 46. When the lever 46 is pressed toward the lever 21, the spreader 48 will spread the latches 15, whereby their hooks 15' will be withdrawn from the lever 21, permitting the latter to be swung outwardly, whereby the

hook 20 will swing toward the article A and the gripping action will be relieved. The bail may be disengaged from the hook 20 and the wrench thus removed.

Various changes in the size and construction of the parts as well as modifications, may be made without departing from the spirit of the invention.

What we claim, is:

1. In a pipe wrench, a head, a hook lever mounted on the head, a flexible jaw for gripping an article, said jaw having a bail at one end engaging the hook lever, and a handle supporting the head. 75
2. In a pipe wrench, a head, a hook lever mounted on the head, a flexible jaw for gripping an article, said jaw having a bail at one end engaging the hook lever, a handle supporting the head, and means for taking up the slack in the flexible jaw. 80
3. In a pipe wrench, a head, a hook lever mounted on the head, a flexible jaw for gripping an article, said jaw having a bail at one end engaging the hook lever, a handle supporting the head, and means for detachably securing the lever for holding the jaw in engagement with the article. 85
4. In a pipe wrench, a head, a hook lever mounted on the head, a flexible jaw for gripping an article, said jaw having a bail at one end engaging the hook lever, a handle supporting the head, means for detachably securing the lever for holding the jaw in engagement with the article, and means for taking up the slack in the flexible jaw. 90
5. In a pipe wrench, a head, a handle supporting the head, a carriage in which the handle is mounted, a flexible loop, a flexible jaw carried by the loop, a hook lever mounted on the head and engaged by the loop, a fastening device for the lever, and a take up device for the cable mounted on the carriage. 105
6. In a pipe wrench, a head, a handle supporting the head, a carriage in which the handle is mounted, a flexible loop, a flexible jaw carried by the loop, a hook lever mounted on the head and engaged by the loop, a fastening device for the lever, a take up device for the cable mounted on the carriage, and means for releasing the fastening device to free the lever. 110
7. In a pipe wrench, a head, a handle, a spring sustained cross head in which the handle is mounted, a looped cable supported by the head and having its ends attached to the carriage, a flexible jaw carried by the loop, a hook lever mounted in the head and engaging the loop, and means for fastening the lever in position. 120
8. In a pipe wrench, a head, a handle supporting the head, a hook lever mounted in the head, a cable loop supported on the head, a plurality of blocks mounted in the loop and constituting a jaw, a bail at the 125

end of the loop engaging the hook lever, spring latches carried by the head and engaged by the lever, and means for spreading the latches to release the lever.

5 9. In a pipe wrench, a head, a handle on which the head is mounted, a flexible jaw having a detachable hook engaging member at one end, a lever pivoted on the

jaw and having a hook for engagement with said member, a latch on the head for holding the lever, and means for releasing the latch to free the lever. 10

In testimony whereof we affix our signatures.

FELIX E. VOORHIES.
OSCAR V. JONES.
